WINDER FOR COLLAPSIBLE TUBES

Jack M. Baume, Bronx, and Gordon Powell,
New York, N. Y.

Application April 28, 1954, Serial No. 30,228

Term of patent 7 years

(Cl. D4—3)

Fig. 1

Fig. 2

Fig. 3

Figure 1 is a front elevational view of a winder for collapsible tubes showing our new design.

Figure 2 is a top plan view of the winder for collapsible tubes shown in Figure 3.

Figure 3 is a side elevational view of the winder for collapsible tubes shown in Figure 1.

We claim:

The ornamental design for a winder for collapsible tubes, as shown.
